United States Patent Office

Des. 220,127
Patented Mar. 9, 1971

220,127

SCALE

Robert A. O'Neil, Glen Ellyn, and Stefan A. Unger,
Chicago, Ill., assignors to Borg-Erickson Corporation,
Chicago, Ill.

Filed May 7, 1969, Ser. No. 17,054

Term of patent 14 years

Int. Cl. D10—99

U.S. Cl. D52—10

FIG. 1.

FIG. 2.

FIG. 3.

FIG. 4.

FIG. 1 is a perspective view of a scale, showing our new design;

FIG. 2 is a top plan view of the scale shown in FIG. 1;

FIG. 3 is a front view of the scale shown in FIG. 1;

FIG. 4 is a side view of the scale viewed from the right of FIG. 2.

The broken lines are shown for illustrative purposes only and form no part of the claimed design.

We claim:

The ornamental design for a scale, substantially as shown and described.
